UNITED STATES PATENT OFFICE.

EVERETT L. STARR, OF PROVIDENCE, RHODE ISLAND, ASSIGNOR TO FULFORD MFG. CO., OF PROVIDENCE, RHODE ISLAND, A CORPORATION OF RHODE ISLAND.

FASTENER.

Application filed September 6, 1928. Serial No. 304,251.

This invention relates to a fastener; and has for its object to provide a socket member having a head or cap of a single piece of material which is so shaped as to provide a broad, 5 side edge and cause the same to have an appearance of substantial thickness.

With these and other objects in view, the invention consists of certain novel features of construction, as will be more fully described, and particularly pointed out in the appended claims.

In the accompanying drawings:

Fig. 1 is a top plan view of the head or cap of the socket member of a fastener of the type 15 which may be secured to a glove or the like.

Fig. 2 is a bottom view thereof.

Fig. 3 is an edge elevation.

Fig. 4 is a top plan view of the blank from 20 which the cap is formed.

Fig. 5 is a side elevation of the blank drawn into cup shape.

Fig. 6 is a sectional view showing the head or cap as secured to the fabric to which the socket member is attached by means of a 25 flanged stud receiving part.

Figures 7 and 8 are respectively a top plan view of the blank for forming the stud receiving portion, and a sectional view of the completed stud receiving portion before it is 30 locked into the cap.

It has been customary to make the front or cap portion of the socket member for a snap fastener, which is to have a thick edge, of two pieces of material, the foundation usually being 35 of metal, with a thick celluloid covering folded about it by heat and pressure which molds it to form a broad edge or bead at substantially right angles to the general plane of the head and it is found that this shape of 40 button is preferable in the trade to one having a sharp edge formed by the bottom wall meeting the top wall at an angle, and in order to make the head or cap portion of the socket member of a single piece of material and yet 45 obtain this broad edge effect, I have formed the same from sheet stock cut and drawn in such a way as to make a distinct edge or bead on the button head and yet make the same out of a single piece of material thus 50 eliminating the two pieces of stock heretofore necessary for obtaining this desired result; and the following is a detailed description of the present embodiment of this invention il-

lustrating the preferred means by which these advantageous results may be accomplished: 55

With reference to the drawings, 10 designates a blank cut out to form projections 11 and notches 12 therebetween, which is drawn into the shape illustrated in Fig. 5 with a top plate 13 having a convex outer surface and a correspondingly concaved inner surface with a wall 14 extending therefrom cylindrically shaped at substantially right angles to the general plane of the top plate.

The wall 14 may be defined as a side wall, as 65 it is of an extent to give breadth of edge surface or thickness to the head or cap of the socket member while the bottom is formed by turning the projections 11 and a portion of the stock 12 from which they extend inwardly, which latter is to form a portion of the 70 bottom wall at substantially right angles to the wall 14, as clearly illustrated in Fig. 3 and the projections 11 which are folded inwardly to form this bottom wall snugly about 75 each other, as illustrated in Fig. 2, to form a substantial unbroken bulging surface 16 with an opening 17 therethrough for the reception of the stud-receiving portion 18 of the socket member.

The edge of the blank is serrated to lessen the resistance on the tools which bend the metal inwardly. The material 19 to which the socket member of the fastener is secured is clamped in position between the flange 20 85 of the stud receiving part of this member as it is forced into position to spread and outwardly flare, its shank 21, as illustrated in Fig. 6, bending portions beneath the bottom wall of the head or cap member to securely 90 lock it in position and press the material 19 against the bulging portion 16 which is in a measure somewhat resilient to firmly hold the socket member in position on the material, the bulging portion of the bottom also spacing 95 the head or cap from the material which gives to the button a desirable appearance and further sets off the wide marginal edge thereof.

The stud-receiving portion 18 is formed of sheet stock blanked out as illustrated in Fig. 7, after which it is folded into substantially cup shape, as shown in Fig. 8, with a shank 21 and flanges 20 in which shape it is forced inwardly thru the opening 17. The closed end 22 of the shank engages the top plate 13 100 and as pressure is applied the walls bend out- 105

wardly at the weakened notched points 23 shaping themselves as illustrated in Fig. 6, to securely lock the two parts of the socket member together.

5. It will be apparent that I have provided a structure by which a wide edge giving a desirable substantial thickness to the button is provided and yet the same is made in a single piece of sheet stock, which appearance in common practice has required two pieces of stock to produce.

10 The foregoing description is directed solely towards the construction illustrated, but I desire it to be understood that I reserve the 15 privilege of resorting to all the mechanical changes to which the device is susceptible, the invention being defined and limited only by the terms of the appended claims.

I claim:

20 1. A snap fastener socket member formed of a single piece of material, comprising a top plate, a side wall extending at substantially right angles therefrom a substantial distance, and a bottom wall extending 25 inwardly at substantially right angles to said side wall and having a bulging middle portion with an opening therein for a stud-receiving part, whereby said side wall forms a distinct bead.

30 2. A snap fastener socket member comprising a sheet material top plate, an integral side wall extending therefrom for a substantial distance at right angles to the material to which the member is to be attached, a bottom 35 wall extending inwardly from said side wall at right angles thereto with a bulging middle portion having an opening therein, and a stud-receiving part in said opening flaring outwardly beneath said bottom wall and having 40 a flange to engage one side of the ma-

terial to which the member is fastened to hold the material firmly in engagement with the bulging portion of said bottom wall.

3. A snap fastener socket member comprising a sheet material top plate having an outer 45 convex surface and an inner concaved surface, a cylindrical side wall extending therefrom for a substantial distance at right angles to the material to which the member is to be attached and at right angles to the general 50 extent of the top plate, a bottom wall extending inwardly from said cylindrical side wall at right angles thereto with a bulging middle portion having an opening therein, and a stud-receiving part in said opening flaring 55 outwardly beneath said bottom wall and having a flange to engage one side of the material to which the member is fastened to hold the material firmly in engagement with the bulging portion of said bottom wall and space 60 the cylindrical side wall therefrom.

4. A snap fastener socket member comprising a sheet material top plate, an integral side wall extending therefrom for a substantial 65 distance at right angles to the material to which the member is to be attached, a bottom wall extending inwardly from said wall at right angles thereto with a bulging middle portion having an opening therein, and a stud-receiving part in said opening, said stud- 70 receiving part having a closed end and a shank weakened at a point to permit outward bending beneath said bottom wall and a flange at the open end of the stud-receiving part to hold the material firmly in engagement with the bulging portion of the bottom wall.

75 In testimony whereof I affix my signature.

EVERETT L. STARR.
